CLAUDE U. TYRRELL, OF LOS ANGELES, CALIFORNIA

FOLDABLE TOY MONOPLANE

Application filed July 1, 1930. Serial No. 465,096.

This invention relates to improvements in foldable flying toys adapted to be projected by a catapult or other means.

The prime object of my invention broadly stated, is to produce a foldable flying toy so formed from a suitable material, as, for example, sheets of cardboard or quite stiff paper or wood, that in outline, especially in midair, it quite closely simulates the appearance of

10 the wing, chassis and rudder of a real plane.

More specifically stated, the object of my invention is a flying toy closely imitating in outline the wing, chassis and rudder of a real plane, the construction of which is such that 15 the wings may be folded back against the body for storage and propulsion and will be urged into open position, so that following the propulsion of this toy plane in its folded condition to the limit of its upward movement 20 in the air, the folded wings are automatically spread apart and the toy glides.

Another object of my invention is to provide a simple and effective means adapting a plane of the construction above described to 25 be propelled in its folded condition upwardly in the air by means of a catapult, or downwardly by hand from an elevation.

With these ends in view, my invention finds embodiment in certain features of novelty in 30 the construction, combination and arrangement of parts by which the said objects are attained, all as hereinafter fully described with reference to the accompanying drawings and more particularly pointed out in the 35 claims.

In said drawings,—

Fig. 1 is a perspective view of a foldable monoplane flying toy in which my invention finds its embodiment with the wings in folded position for propulsion; Fig. 2 is a perspective view of a catapult for propelling the toy; Fig. 3 is a perspective view of the monoplane in its open position for gliding; Fig. 4 is a section as seen on the line 4—4 of Fig. 3; and Fig. 5 is a perspective view of a fragment of the toy showing the wings partially open and disclosing the joint between body and wings.

Referring more particularly to the drawings, the body of the toy comprises a rod 6,

preferably made of wood or some lightweight material. A ferrule 7 of rubber or any other suitable material is mounted on the rod at the head end. This ferrule serves primarily as a balancing weight and also acts as an impact head. A slit is formed in the rod to receive a triangular member 8 which may be made of stiff cardboard and serve as a catapult catch. The empennage consisting of stabilizing planes is mounted at the tail end and comprises duplicate vertical fins 9 which are preferably made of cardboard and may be formed of a single sheet folded upon itself with the creased portion enclosed in a slit in the rod. At the outer end heads 9—a are provided to be passed through slits in a horizontal fin 10. This section provides for easy assemblage of the parts and for packing of the folded toy. The assemblage just described forms a fuselage body.

The wings are secured to the body intermediate the ends of the latter. A pleat hinge is provided consisting of two leaves 11, preferably made of flexible fabric or paper. The mid crease 11—a is disposed in a slit in the rod and the ends of the leaves are secured to wings 12 to form joints 11—b extending diagonally along the wings. The wings 12 may be made of balsa wood or any other suitable light weight material and are hinged together at the center as indicated by 13. The pleat hinge forms a feathering hinge, such that the wings may be folded to lie laterally against the body as indicated in Fig. 1. In spread gliding position, the wings are shown in Fig. 3, and will have been turned through an angle of ninety degrees. In spread position, the leaves 11 of the pleat hinge are extended to lie flat against the wings. Reinforcing strips 14 are shown on the wings at the joint 13. On the upper side of the wings are hooks 15 adapted to receive an elastic band 16 which is of such length that the band will be under tension when the wings are folded as shown in Fig. 1 so that the wings are urged into spread position as shown in Figs. 3 and 4.

A catapult is shown in Fig. 2 for projecting the toy. This consists of rigid stem 17 and an elastic band 18.

The toy is packed in collapsed position as shown in Fig. 1, but the horizontal fin is demounted from the vertical fins 9. In packing, the band 16 is not in position on the hook, but may be placed around the wings 12 at the rear ends serving to hold them in collapsed position. When it is desired to use the toy, the horizontal fin 10 is placed in position upon the vertical fins and the band 16 mounted on the hooks. The folded toy is then in a position shown in Fig. 1. The wings 12 tend to open out into spread position. They are held together at the rear by the fingers of one hand of the operator, and the band 18 of the catapult is looped over the catch 8 on the body. Band 18 is then stretched and the toy released so that it will be projected upwardly. The inertia of the wings and the pressure of the air tend to hold the wings in folded position. As the toy loses speed the band 16 gradually opens the wings to gliding position shown in Fig. 3. Thereupon, the plane glides to the ground.

It is obvious that I have provided a toy economical of construction, simple and few in parts, easy of manipulation and which will afford entertainment. It is compact when folded and may be packed in a small space. The parts subject to wear and breakage are easy of repair and the materials for such repair are easily available.

What I claim is:—

1. A foldable flying toy comprising an elongated body, wings jointed to each other, a pleat hinge securing said wings to the body to enable the wings to be feathered from a spread gliding position outstanding from said body to a closed position laterally lying against and ranging longitudinally of said body, said hinge comprising a pair of leaves attached at the intermediate joint line to said body and attached at their outer ends to the wings along joint lines converging toward the intermediate joint line, hooks disposed on said wing and an elastic band passed over said hooks urging said wings from closed to spread position.
2. A foldable aeroplane flying toy comprising an elongated body, wings jointed to each other, a pleat hinge securing said wings to the body to enable the wings to be feathered from a spread gliding position outstanding from said body to a closed position laterally lying against and ranging longitudinally of said body, said hinge comprising a pair of leaves attached at the intermediate joint line to said body and attached at their outer ends to the wings along joint lines converging toward the intermediate joint line, hooks disposed on opposite sides of the wing joint, an elastic band passed over said hooks urging said wings from closed to spread position, and a catch for a catapult depending from said body.
3. A foldable aeroplane flying toy com-

prising a rod like body, wings jointed to each other, a flexible leaf hinge securing said wings to the body to enable the wings to be feathered from a spread gliding position outstanding from said body to a closed position laterally lying against and ranging longitudinally of said body, hooks disposed on opposite sides of the wing joint, an elastic band passed over said hooks urging said wings from closed to spread position, a slit in said rod, a catapult catch disposed in said slit, said hinge having an intermediate crease forming a joint disposed in a slit in said rod and leaves secured to said wings by joints converging toward said crease.

In witness that I claim the foregoing I have hereunto subscribed my name this 23rd day of June, 1930.

CLAUDE U. TYRRELL.
